(57) **CLAIM**

The ornamental design for an information handling system, as shown and described.

DESCRIPTION

FIG. 1 is a front perspective view of the information handling system comprising the present invention; FIG. 2 is an enlarged view of a portion of the front perspective view thereof;

FIG. 3 is an enlarged view of another portion thereof;

FIG. 4 is a front view thereof;

FIG. 5 is an enlarged view of a portion of the front view thereof;

FIG. 6 is a rear view thereof;

FIG. 7 is a right side view thereof;

FIG. 8 is an enlarged view of a portion of the right side view thereof;

FIG. 9 is a left side view thereof;

FIG. 10 is a top view thereof;

FIG. 11 is a bottom view thereof;

FIG. 12 is a front perspective view of a second embodiment thereof;

FIG. 13 is an enlarged view of a portion of the front perspective view thereof;

FIG. 14 is an enlarged view of another portion thereof;

FIG. 15 is a front view thereof;

FIG. 16 is an enlarged view of a portion of the front view thereof;

FIG. 17 is a rear view thereof;

FIG. 18 is a right side view thereof;

FIG. 19 is an enlarged view of a portion of the right side view thereof;

FIG. 20 is a left side view thereof;

FIG. 21 is a top view thereof; and,

FIG. 22 is a bottom view thereof.

Broken lines shown in the drawings illustrate portions of the information handling system, and form no part of the claimed design.
